UNITED STATES PATENT OFFICE.

ELLIS H. MORRIS, OF CANTON, OHIO.

BAND-CUTTER AND FEEDER.

SPECIFICATION forming part of Letters Patent No. 435,942, dated September 9, 1890.

Application filed December 26, 1889. Serial No. 335,088. (No model.)

To all whom it may concern:

Be it known that I, ELLIS H. MORRIS, a citizen of the United States, and a resident of Canton, county of Stark, State of Ohio, have 5 invented a new and useful Improvement in Band-Cutters and Feeders, of which the following is a full, clear, and exact description, reference being had to the accompanying drawings, making part of this specification.

10 My invention relates to improvements in band-cutters and feeders for thrashing-machines.

The object is to provide means for cutting the bands placed about sheaves of grain to 15 distribute the grain evenly over an endless apron or carrier, by which the grain may be fed to the thrashing-cylinder evenly.

20 My invention also relates to improved means for regulating the supply of grain to the thrashing-cylinder without changing or interfering with the motion of the thrashing-machine.

25 With these ends in view my invention consists in certain features of construction and combination of parts, as will be hereinafter described, and pointed out in the claims.

30 Figure 1 of the accompanying drawings is a right-hand side elevation illustrating my invention as applied to a thrashing-machine, having a part of the side-board removed to show interior detail. Fig. 2 is a front elevation looking into the front end of the machine. Fig. 3 is an elevation of the right-hand side of the machine, partly sectional, showing interior details. Fig. 4 is a perspective of a 35 fragment of the band-cutting mechanism enlarged; Fig. 5, a view in cross-section of the feeding-cylinder and side view of the spikes. Fig. 6 is a longitudinal vertical sectional view of the feed-cylinder; Fig. 7, a plan view showing the location of the several parts. Fig. 8 is a front end elevation showing the driving 40 mechanism; and Fig. 9 is a fragment of the carrying-apron, showing the cross-cleat and metal-toothed rake.

45 As my invention is applicable alike to many of the thrashing-machines now in use, I will proceed with the description, referring only to the thrasher parts as conjunctional thereto.

50 A represents the body portion of the machine as shown in several of the figures of the drawings. It is quadrilateral in form and is constructed of side and end portions, as A

and z, and frame in such form and of such strength as to form a support for the machinery belonging thereto. The said frame is secured to and is supported on the arms B of 55 the thrasher in front of the thrashing-cylinder.

At the bottom portion of the body A are rollers R and R^a, the former supported in a 60 suitable bearing in a swinging frame Q', the latter in adjustable bearings O. About said rollers is placed an endless conveyer apron or feeder K, having on each side thereof sprocket-chains. The lower chain after 65 engaging the lower side of sprocket-wheel J passes upwardly and over the roller M. The said carrier is further provided with cross-slats L, to each of which is secured a metal plate R², having its upper edge serrated, as 70 shown in Fig. 9. Over said carrier is placed a feed-cylinder M', preferably constructed of sheet metal, secured to cast-metal heads a a', the latter having cast integral therewith an eccentric portion H, having about its periphery 75 an annular groove a², and the former having cast integral therewith a bevel-wheel Y. The cylinder is supported on and rotates about a cranked shaft U, the heads a and a' being supported on the journal portions V 80 and W. The cylinder is further provided with apertures S, through which the teeth are projected, said teeth having an eye portion d⁴, (see Fig. 5,) that embraces the central portion of the cranked shaft U. The apertures S may be placed in alignment with the body of the cylinder or spirally about it, as shown in Fig. 3. The shaft U is supported in suitable bearings a³ in the frame of the body A, and on the front end portion of said 85 shaft is secured a segment A' of a worm-wheel, which is engaged by a worm B', secured to a shaft a⁵. (See Fig. 2.) Said shaft is supported in journals a⁶ and projects outside of the body of the machine, and on the 90 end thereof is secured a pulley C', having coiled about it a rope D', the free ends of which are placed in convenient reach of the operator and marked "fast" and "slow." The object of said rope is to rotate the worm B', 95 and by its engagement with the segment A' to rotate the shaft U to throw the eccentric middle portion inwardly, as shown in Fig. 2, by which the teeth will be thrown out a greater

distance into the straw to feed more rapidly, or turned back to draw the teeth in and thereby check the flow of straw and grain to the carriers below and the thrashing-cylinder. By drawing on the fast end of the rope D' the shaft and teeth will be placed in position, as shown in Fig. 2, and by drawing on the end marked "slow," the pulley C' will be rotated, and by it the shaft a⁵ and worm B', engaging the segment A', will turn the segment outwardly and upwardly and the middle or eccentric portion of the shaft U downwardly and outwardly, thereby drawing the teeth back into the cylinder to prevent them from entering into and feeding down the straw. It will be noticed that this cylinder is placed on a line at right angles to the thrashing-cylinder and in line with the movement of the carrier.

It will be noticed that the movement of the ropes referred to will rotate the sprocket-wheel b³ on the worm-shaft a⁵ to move the band-cutter to and from the cylinder, as will be hereinafter more fully explained.

To drive the cylinder M', a shaft G is placed across the rear portion of the body of the machine, supported and rotated in journal-boxes a', on the left-hand end of which is placed a bevel gear-wheel X, the teeth of which engage the teeth of the bevel-wheel Y on the cylinder-head, and on said shaft is secured an eccentric W', and outside of the body A a sprocket-wheel a⁸. The said wheel has a chain engagement with a similar wheel H, by which power is communicated to the sprocket-wheel J to drive the carrier K. On the right-hand end portion of said shaft G is loosely mounted a band-wheel or pulley C, which engages the main driving-belt D of the thrashing-machine as it passes from the pulley z' on thrashing-cylinder shaft forward under and about the pulley C and up and over the idler E, as shown in Fig. 1.

The pulley C is held in place on the shaft by a removable plate Y', forming an inwardly-projected collar to engage an annular groove at the end of the shaft, and to engage the said pulley with the said shaft a clutch is provided on the inner end portion of the hub of said pulley, and on the shaft a clutch-sleeve A², secured from rotation on said shaft by a feather B² in the usual way, said sleeve having at its inner end an annular collar, in which are placed the prongs of the sprung-lever C². The said lever is pivoted to a supporting-bracket D², the front end being extended forward a little distance and secured by a link E² to a hook E³ on the side of the body A, by which means the clutch on the sleeve A² is held in engagement with a similar clutch on the inner end of the hub of the driving-pulley C. A spring J² is provided, the energy of which is exerted against the free end of the lever C² to hold the clutch A² from engagement with the clutch on the hub of the pulley C when the link E² is released from the hook E³.

The knife H', provided to sever the bands by which the grain is bound into sheaves, is constructed of a single blade of steel having a serrated cutting-edge, as shown in Fig. 4, the ends of the blade being secured in the brackets H² and J'.

A finger-bar Q² formed of angle-iron, as shown in Fig. 4, is provided, having fingers R' secured thereto to embrace and project beyond the knife H'. The said bar is placed in slides S' in the brackets J' and H². A wrist-pin T' is secured to said bar, to which one end of a connecting-rod U' is secured by a journal-box of spherical form, the other end of said rod being provided with a yoke or strap to embrace the eccentric W', thus providing means for reciprocating the finger-bar Q², and fingers by which the cords or bands about the sheaves of grain are drawn over the edge of the cutter H' and severed. The brackets H² and J' have a sliding connection with the supporting-frame to provide for a movement of the knife H² to and from the cylinder M' to open or close the throat or space between the cylinder and the knife, which movement is effected by means of the screws F' and G', turned into the lugs b² on the brackets J' and H², the heads of said screws journaled in the body or frame A at b', and on said ends is mounted sprocket-wheels b², and on the worm-wheel shaft a⁵ is mounted a similar wheel b³ to correspond with the wheels b². A sprocket-chain E' is placed about said wheels, as shown in Fig. 3, and by drawing on said chain, the screws F' and G' and the worm B' will be rotated to simultaneously move the band-cutter to and from the cylinder M' and the teeth T out of or into the said cylinder to increase or decrease the means for supplying grain to the thrasher or to stop the supply entirely without in any way interfering with the movements of the thrasher. To distribute the straw over the apron K, a vibrating finger P² is provided, as shown, pivotally secured to a pedestal Q³, and is vibrated by a connecting-rod N², one end of which is pivotally secured to the finger P², and the other end is pivotally secured to a swinging bar L², as shown in Fig. 8, said swinging bar having a pivoted connection with a part of the frame, as shown at M², Fig. 2, the swinging bar being shown by dotted lines, the upper end of said bar having a link-connection with the eccentric K² on the cylinder-head H. As the cylinder M' is rotated the eccentric will sway the bar L², which by its connections therewith will vibrate the finger P² over the carrier K to spread or distribute the straw. As shown in Fig. 3, the rear portion of the carrier-supporting frame is pivoted about a sleeve projected inwardly from the journal-box of the shaft supporting the sprocket-wheel J, and may be dropped down, as shown, to provide access to the thrashing-cylinder and concave.

In the hopper L' (shown in Fig. 2) there is provided a yielding breast-plate N', extending the length of the feeder, and hinged at the upper side of the top of the body, as

shown at O'. The lower side portion is supported on springs P', the object of which is to provide a yielding pressure plate or board by which the sheaves are held against the cylinder.

In operation, when the thrashing-machine is put in operation the driving-belt D will rotate the driving-pulley C in the direction shown by the arrow, the bevel-wheel X, engaging a similar wheel Y on the cylinder M', will rotate said cylinder inwardly, and the sheaves of grain thrown into the hopper L' (shown in Fig. 2) will be drawn by the teeth down against the fingers of the band-cutter, which are reciprocated by the eccentric W'. After the band is cut the straw will fall onto the carrier K, which is driven by the sprocket-chain placed about the sprocket-wheels a⁵ and H on the cross-shaft G and the shaft carrying the sprocket-wheels J, respectively, and to distribute the straw on the carrier the finger P² is vibrated by the eccentric K², as before stated. To regulate the supply of grain to the thrasher, a pull on the rope D', marked "fast," will rotate the worm B' to project the teeth T and rotate the screws F' and G' to increase the space between the cylinder and the band-cutter, and thereby increase the supply of grain to the carrier and thrasher, and a pull on the rope marked "slow" will reverse the operation by closing the space between the band-cutter and the cylinder M', and drawing in the teeth, as hereinbefore stated, to check the supply of straw or grain; or the feeder may be stopped entirely by releasing the link E², thereby disengaging the clutch A² from the hub of the wheel C by the use of the lever C².

Having thus fully described the nature and object of my invention, what I claim as new, and desire to secure by Letters Patent, is—

1. The combination, with a thrashing-cylinder, of a carrier K, a feed-cylinder M', having teeth T supported above and over said carrier and rotating transversely thereto, a knife H', and a reciprocating finger-bar Q², having fingers R' to sever the bands, substantially as described, and for the purpose set forth.

2. The combination, with a thrashing-cylinder, of a feed-cylinder placed in front of and at right angles to said thrashing-cylinder and having teeth the projecting portion of which may be varied at will during the operation of feeding grain to be thrashed, substantially as described, and for the purpose set forth.

3. The combination, with a thrashing-cylinder and a feeding-cylinder placed at right angles thereto and having rotary adjustable teeth, of a knife and finger-bar to cut the band, and a carrier to carry the grain to the thrashing-cylinder, substantially as described, and for the purpose set forth.

4. In combination, the cylinder M', pro-

vided with perforations, the cranked shaft about which the cylinder revolves, teeth mounted on the cranked shaft and projected through the perforations, a band-cutter, and means for adjusting the band-cutter toward and away from the cylinder, substantially as set forth.

5. In combination, the cylinder provided with perforations, the cranked shaft about which the cylinder revolves, teeth mounted on the cranked shaft and projected through the perforations, a band-cutter, and means for simultaneously adjusting the shaft and the band-cutter, substantially as set forth.

6. In combination, the carrier, the feed-cylinder and band-cutter arranged transversely to the movement of the carrier, and a vibrating spreading-finger the free end of which has a sweeping movement back and forth across the face of the carrier transversely to its movement, substantially as set forth.

7. In combination with the cylinder M', supported on and rotating about a shaft having a portion eccentric to said cylinder, teeth journaled about said eccentric portion, the free end projected through the wall of said cylinder, a worm-wheel mounted on said shaft, a worm to engage said wheel to rotate said shaft for the purpose of adjusting the eccentric portion thereof in said cylinder, a band-cutter secured in movable bearings, and a connection between the movable bearings and said worm, for the purpose set forth.

8. The combination, with the cylinder M', of the stationary band-cutter knife H', the reciprocating finger-bar, screw-shafts F' and G', worm-wheel A', worm B', shaft a⁵, pulley C', and ropes D', by which said parts may be adjusted and held in desired adjustment, substantially as described, and for the purpose set forth.

9. In a band-cutter and feeder, the combination, with the carrier, the feeding mechanism located over the carrier, and the thrashing-cylinder at the rear of the carrier, of a carrier-frame having its rear portion pivoted about the carrier-actuating shaft and adapted to fold down with respect to the frame of the machine, substantially as described, and for the purpose set forth.

10. The combination, with a feed-hopper and band-cutter and feed-cylinder, the latter provided with feed-teeth adjustable across the throat, of a yielding breast-plate whereby the throat leading from the hopper to the feed-cylinder may automatically enlarge and contract, substantially as described, and for the purpose set forth.

In testimony whereof I have hereunto set my hand this 21st day of December, A. D. 1889.

ELLIS H. MORRIS.
